UNITED STATES PATENT OFFICE

HARRY D. ROCHEVILLE, OF LOS ANGELES, CALIFORNIA

ADJUSTABLE-CAMBER AEROFOIL

Application filed March 25, 1929. Serial No. 349,619.

This invention relates to aeroplane aerofoils, such as the supporting planes and apertains particularly to a variable curvature of the cross section longitudinally of the 5 aerofoil. As illustrative of the inventive idea, an aerofoil curve known as the Clark Y or modification thereof are commonly used for speed, while a more arched curve known as the Gottingen 387 or modifications there- 10 of have greater sustaining power with relation to head resistance than the Clark Y or modifications. An aerofoil having a Gottingen 387 curve or modification is more useful to secure great lift at slow speeds so as 15 to add to the stability of an aeroplane in taking off and in landing. It is desirable to have a Gottingen 387 curve or modifications thereof for taking off and landing and a Clark Y curve or modifications thereof for 20 cruising or making speed. The present invention relates to an aerofoil structure arranged so that the thickness of the aerofoil and its curvature may be changed.

The objects of this invention are to pro- 25 vide an aerofoil having any or all of the following features: a variable camber; an aerofoil structure operable at the will of the pilot to change the thickness of the aerofoil; an aerofoil structure of the character before 30 described in which the curvature may be changed from one predetermined limiting curve to another; an aerofoil structure as before described wherein the curvature may 35 set at any intermediate curve between the limiting curves; an aerofoil of the character described having a pivoted trailing edge portion and mechanism to effect such changes in the aerofoil.

40 These objects together with other objects in corresponding accomplishment are obtained by means of the embodiment of my invention, illustrated in the accompanying drawing, in which:—

45 Fig. 1 is a plan view of a fragment of a fuselage showing one aerofoil with the covering broken away to show the frame work; Fig. 2 is a section from front to rear of an aerofoil in collapsed position; Fig. 3 is a 50 similar cross section with the aerofoil in ex-

panded condition; and Fig. 4 is a fragmental section at right angles to Figs. 2 and 3.

Referring more particularly to the drawings, A indicates the fuselage of an aeroplane, only a fragment thereof being shown. 55 Mounted on the fuselage in any suitable manner is shown an aerofoil embodying my invention. This aerofoil is shown with an entering or front portion B and a trailing portion or flap C. The trailing portion C is 60 pivotally connected to the entering portion and may be maintained in adjusted position by means hereafter described. The arrangement is such as to change the camber of the aerofoil with change in pivotal position of 65 the trailing portion. An aileron D of any well known type of construction is provided on the trailing portion and completes the aerofoil.

Referring to the front portion of the aerofoil, a spar 6 extends the length thereof adjacent the entering edge and a spar 7 is provided at the rear of the front portion. The spars 6 and 7 are preferably built up includ- 70 ing braces so that lattice spars are provided for passage therethrough of the operating parts of the aerofoil frame. The front portion has a frame work consisting of alternate fixed and variable ribs. The fixed ribs are marked 8 and may be of the usual construc- 75 tion. These ribs are anchored to a nose piece 10 extending across the entering edge. As 80 illustrative of the invention, the fixed rib is shown with a Clark Y curve.

The variable rib comprises an upper cover- 85 ing supporting section including articulated rafters, each rafter consisting of joints marked 11a, 11b and 11c. Joints 11a are hinged as indicated by 12 to the cross mem- 90 ber 10. Joints 11b are hinged to joints 11a as indicated by 13, and joints 11c are con- 95 nected by elongated slot and pin connections 14. The joints 11c are connected by hinges to the spar 7. A jointed stretcher spans each rafter. Each stretcher comprises a joint 16a connected to a joint 16b by an elongated slot and pin connection 17. Joints 16a are pivot- 100 ally connected by the hinge 12 to the cross member 10. Joints 16b are connected to the joints 11c by hinges 18. Arms 19 are pro-

vided on the stretcher joints 16b. A yoke 20 is provided on each rafter joint 16b for the accommodation of eccentrics. The rafters are stiffened by suitable braces and connected 5 to the stretcher joints by brace members 21. A shaft 22 extends the length of the variable ribs and has mounted thereon eccentrics 23 operating in the yokes 20, so that upon rotation of the shaft, the variable rafters will 10 be raised or lowered to change the upper curve. The shaft 22 extends toward the fuselage and any suitable mechanism may be provided for turning the shaft from the fuselage. Such mechanism forms no part of the 15 present invention and is not shown herein. The ribs are provided with a suitable flexible covering 24 which follows the variable ribs in their changes. In the arms 19 are holes.

The trailing portion C of the aerofoil consists of a rigid frame 25 built up in any suitable manner and having a covering 26. Extending across the front of the trailing portion is a cross member 27 hinged at 28 to the spar 7 so that the trailing portion may be 25 rocked through an angle. Gusset members 29 are provided in the angular opening between the cross member 27 and the spar 7. Tying the cross member 27 to the arm 19 are tie members 30. It will be noted that 30 upon buckling of the stretcher, the trailing portion will be swung downwardly.

In the drawing, the variable ribs when in their upper position are shown to form substantially a Gottingen 387 curve. Movement 35 of the eccentric shaft 22 causes the upper covering to be arched to a greater curvature and the aerofoil to be thickened. At the same time the trailing portion is rocked downwardly so that the trailing portion acts as an air brake and will decrease the speed. The amount of angle of the trailing portion may be adjusted by the tie member through 40 a turn buckle 31 or by changing the tie member connection between the arm 18 and the gusset members 29 using different holes. Thus, adjustability of the angle of the trailing portion is provided for. In taking off, the aerofoil may be thickened, and after a suitable altitude has been reached, the aerofoil 45 may be collapsed. In landing the aerofoil may be again thickened. This is done at the will of the pilot. It will be noted that the fixed ribs maintain constant the shape of the lower side of the aerofoil and limit the 50 shape of the upper side at its minimum thickness. In design, the positions of the yokes 20 and eccentrics in relation to the stretchers affects the curvature as well as the location of connections 13 in the articulated rafters.

30 What I claim is:—

1. An aerofoil comprising a front section and a trailing section; said front section having a covering, a frame supporting said covering and including a set of spaced ribs having jointed rafters and a set of fixed rafters,

jointed stretchers supporting the set of articulated rafters, a shaft extending transverse of said ribs, means securing said stretchers to said shaft whereby turning of said shaft bends said stretchers; the trailing section of 70 said aerofoil being pivotally mounted on said front section; an adjustable tie member securing said trailing section to said stretchers to cause rocking of said trailing section with movement of said rafters whereby to 75 change the camber of said aerofoil.

2. An aerofoil structure having a frame for determining the curvature of the upper side and the thickness of the aerofoil: said frame comprising a set of fixed ribs maintaining 80 constant the shape of the lower side of the aerofoil; a set of articulated ribs determining an adjustable curvature of the upper side of said aerofoil, said articulated ribs being pivoted at their front and rear ends in relation 85 to said fixed ribs, each of said articulated ribs comprising a rafter having joints with a plurality of pivotal connections intermediate the ends thereof, and a stretcher having a pivotal connection intermediate its ends 90 whereby it may be buckled; and adjustable means to buckle the stretchers and maintain them in adjusted buckled positions.

3. An aerofoil structure having a frame for determining the curvature of the upper side 95 and the thickness of the aerofoil: said frame comprising a set of fixed ribs maintaining constant the shape of the lower side of the aerofoil; a set of articulated ribs determining an adjustable curvature of the upper side of 100 said aerofoil, said articulated ribs being pivoted at their front and rear ends in relation to said fixed ribs, each of said articulated ribs comprising a rafter having three joints intermediate its ends secured together by pivotal 105 connections and a stretcher having a single pivotal connection intermediate its ends and located intermediate said pivotal connections in its rafter; and adjustable means to buckle the stretchers and maintain 110 them in adjusted buckled positions.

4. An aerofoil structure having a frame for determining the curvature of the upper side and the thickness of the aerofoil: said 115 frame comprising a set of fixed ribs maintaining constant the shape of the lower side of the aerofoil; a set of articulated ribs determining an adjustable curvature of the upper side of said aerofoil, said articulated ribs being pivoted at their front and rear ends in relation to said fixed ribs, each of said 120 articulated ribs comprising a rafter having joints with a plurality of pivotal connections intermediate the ends thereof, and a stretcher having a pivotal connection intermediate its ends whereby it may be buckled; eccentric yokes on said stretchers and eccentrics journalled on said fixed ribs and engaging 125 said yokes whereby to adjustably buckle 130

said stretchers and maintain them in adjusted buckled positions.

5. An aerofoil structure having a frame for determining the curvature of the upper side and the thickness of the aerofoil: said frame comprising a set of fixed ribs maintaining constant the shape of the lower side of the aerofoil; a set of articulated ribs determining an adjustable curvature of the upper side of said aerofoil, said articulated ribs being pivoted at their front and rear ends in relation to said fixed ribs, each of said articulated ribs comprising a rafter having three joints intermediate its ends secured together by pivotal connections and a stretcher having a single pivotal connection intermediate its ends and located intermediate said pivotal connections in its rafter; eccentric yokes on said stretchers, and eccentrics journaled on said fixed ribs and engaging said yokes whereby to adjustably buckle said stretchers and maintain them in adjusted buckled positions.

6. An aerofoil structure having a frame for determining the curvature of the upper side and the thickness of the aerofoil: said frame comprising a set of fixed ribs maintaining constant the shape of the lower side of the aerofoil; a set of articulated ribs determining an adjustable curvature of the upper side of said aerofoil, said articulated ribs being pivoted at their front and rear ends in relation to said fixed ribs each of said articulated ribs comprising a rafter having joints with a plurality of pivotal connections intermediate the ends thereof, and a stretcher having a pivotal connection intermediate its ends whereby it may be buckled; eccentric yokes on corresponding joints of said stretchers, and eccentrics journaled on said fixed ribs and engaging said yokes whereby to adjustably buckle said stretchers and maintain them in adjusted buckled positions.

45 7. An aerofoil structure having a frame for determining the curvature of the upper side and the thickness of the aerofoil: said frame comprising a set of fixed ribs maintaining constant the shape of the lower side of the aerofoil; a set of articulated ribs determining an adjustable curvature of the upper side of said aerofoil, said articulated ribs being pivoted at their front and rear ends in relation to said fixed ribs, each of said articulated ribs comprising a rafter having three joints intermediate its ends secured together by pivotal connections and a stretcher having a single pivotal connection intermediate its ends and located intermediate said pivotal connections in its rafter; eccentric yokes on corresponding joints of said stretchers, and eccentrics journaled on said fixed ribs and engaging said yokes whereby to adjustably buckle said stretchers and maintain them in adjusted buckled positions.

8. An aerofoil structure having a frame for determining the curvature of the upper side

and the thickness of the aerofoil: said frame comprising a set of fixed ribs maintaining constant the shape of the lower side of the aerofoil and having rafters limiting the curvature of the upper side at the minimum thickness of said aerofoil; a set of articulated ribs determining an adjustable curvature of the upper side of said aerofoil, said articulated ribs being pivoted at their front and rear ends in relation to said fixed ribs, each of said articulated ribs comprising a rafter having joints with a plurality of pivotal connections intermediate the ends thereof, and a stretcher having a pivotal connection intermediate its ends whereby it may be buckled; and adjustable means to buckle the stretchers and maintain them in adjusted buckled position.

9. An aerofoil structure having a frame for determining the curvature of the upper side and the thickness of the aerofoil: said frame comprising a set of fixed ribs maintaining constant the shape of the lower side of the aerofoil and having rafters limiting the curvature of the upper side at the minimum thickness of said aerofoil; a set of articulated ribs determining an adjustable curvature of the upper side of said aerofoil, said articulated ribs being pivoted at their front and rear ends in relation to said fixed ribs, each of said articulated ribs comprising a rafter having three joints intermediate its ends secured together by pivotal connections and a stretcher having a single pivotal connection intermediate its ends and located intermediate said pivotal connections in its rafter; and adjustable means to buckle the stretchers and maintain them in adjusted buckled positions. 85 90 95 100

10. An aerofoil structure having a frame for determining the curvature of the upper side and the thickness of the aerofoil: said frame comprising a set of fixed ribs maintaining constant the shape of the lower side of the aerofoil and having rafters limiting the curvature of the upper side at the minimum thickness of said aerofoil; a set of articulated ribs determining an adjustable curvature of the upper side of said aerofoil, said articulated ribs being pivoted at their front and rear ends in relation to said fixed ribs, each of said articulated ribs comprising a rafter having joints with a plurality of pivotal connections intermediate the ends thereof, and a stretcher having a pivotal connection intermediate its ends whereby it may be buckled; eccentric yokes on said stretchers, and eccentrics journaled on said fixed ribs and engaging said yokes whereby to adjustably buckle said stretchers and maintain them in adjusted buckled positions. 105 110 115 120 125

11. An aerofoil structure having a frame for determining the curvature of the upper side and the thickness of the aerofoil: said frame comprising a set of fixed ribs main-

taining constant the shape of the lower side of the aerofoil and having rafters limiting the curvature of the upper side at the minimum thickness of said aerofoil; a set of arti-

5 main thickness of said aerofoil, a set of artic-
ulated ribs determining an adjustable cur-
vature of the upper side of said aerofoil, said
articulated ribs being pivoted at their front
and rear ends in relation to said fixed ribs,
each of said articulated ribs comprising a
10 rafter having three joints intermediate its
ends secured together by pivotal connections
and a stretcher having a single pivotal con-
nection intermediate its ends and located in-
termediate said pivotal connections in its
15 rafter; eccentric yokes on said stretchers, and
eccentrics journalled on said fixed ribs and
engaging said yokes whereby to adjustably
buckle said stretchers and maintain them in
adjusted buckled positions.

20   12. An aerofoil structure having a frame
for determining the curvature of the upper
side and the thickness of the aerofoil: said
frame comprising a set of fixed ribs main-
taining constant the shape of the lower side
25   of the aerofoil and having rafters limiting
the curvature of the upper side at the mini-
mum thickness of said aerofoil; a set of artic-
ulated ribs determining an adjustable cur-
vature of the upper side of said aerofoil, said
30   articulated ribs being pivoted at their front
and rear ends in relation to said fixed ribs,
each of said articulated ribs comprising a
rafter having joints with a plurality of piv-
otal connections intermediate the ends there-
35   of, and a stretcher having a pivotal connec-
tion intermediate its ends whereby it may be
buckled; eccentric yokes on corresponding
joints of said stretchers, and eccentrics jour-
nalled on said fixed ribs and engaging said
40   yokes whereby to adjustably buckle said
stretchers and maintain them in adjusted
buckled positions.

13. An aerofoil structure having a frame for determining the curvature of the upper side and the thickness of the aerofoil: said frame comprising a set of fixed ribs maintaining constant the shape of the lower side of the aerofoil and having rafters limiting the curvature of the upper side at the minimum thickness of said aerofoil; a set of articulated ribs determining an adjustable curvature of the upper side of said aerofoil, said articulated ribs being pivoted at their front and rear ends in relation to said fixed ribs, each of said articulated ribs comprising a rafter having three joints intermediate its ends secured together by pivotal connections and a stretcher having a single pivotal connection intermediate its ends and located intermediate said pivotal connections in its rafter; eccentric yokes on corresponding joints of said stretchers, and eccentrics journaled on said fixed ribs and engaging said yokes whereby to adjustably buckle said stretchers and

maintain them in adjusted buckled positions
In witness that I claim the foregoing I have
hereunto subscribed my name this 12th day of
March, 1929.
